UNITED STATES PATENT OFFICE.

LESLIE JAMES, OF CHICAGO, ILLINOIS.

DISPLAY-RACK.

1,367,051.

Specification of Letters Patent.

Patented Feb. 1, 1921.

Application filed May 28, 1920. Serial No. 384,891.

To all whom it may concern:

Be it known that I, LESLIE JAMES, a citizen of the United States, residing at Chicago, in the county of Cook and State of Illinois, have invented new and useful Improvements in Display-Racks, of which the following is a specification.

The rack which is the subject matter of the present application for patent has been 10 designed more particularly for supporting mattresses in position for display, and the invention has for its object to provide a rack which will support a large number of mattresses, and which is compact so that it takes 15 up but a very small space.

A further object of the invention is to provide a display rack having its supporting members so arranged that the mattresses can be readily placed out of the way and 20 also readily swung outwardly and rotated for inspection.

The objects stated are attained by means of a novel combination and arrangement of parts to be hereinafter described and 25 claimed, and in order that the same may be better understood, reference is had to the accompanying drawing forming a part of this specification.

In the drawing, 30 Figure 1 is a front elevation of the device;

Fig. 2 is a horizontal section on the line 2—2 of Fig. 1, and

Fig. 3 is a perspective view of one of the 35 mattress supporting units.

Referring specifically to the drawing, 5 denotes a rectangular case which is open in front and is large enough to inclose a stack of mattresses 6 of various patterns. The 40 case may be made in any desired size according to the number of mattresses it is to inclose.

At the open front or entrance of the case 5 are mounted two upright posts 7, one at

each end, and from these posts extend horizontal bracket arms 8 arranged in alternate or overlapping order. The inner end of each arm 8 has a sleeve 9 loosely embracing the post 7 so that the arm may be swung horizontally into and out of the case 5. The 45 outer end of each arm 8 carries a rotatable mattress supporting member 10 consisting of a rectangular skeleton frame having at the center a hub 11 seating on an upstanding pivot pin 12 at the outer end of the 50 arm. A sheet 13 of screening or other suitable material covers the frame so that the mattress may be evenly supported. A fragment only of the sheet 13 is shown in Fig. 3.

By the structure hereinbefore described, 60 the mattresses may be supported, one above the other, in the case 5, each mattress being independently supported. It is therefore possible to swing any desired mattress out of the case for inspection, and the mattress 65 may also be rotated as its support 10 is rotatable. When pushed back into the case, the mattresses are effectually protected from being soiled or otherwise damaged.

The structure is very simple, strong and 70 durable, the mattress supporting means being constructed of metal tubing connected by elbows and other standard fittings.

I claim:

The combination of a case having an open 75 front, vertical posts mounted in the case adjacent to the open front thereof, one at each end, horizontal bracket arms pivotally supported by the posts and extending inwardly therefrom in alternate relation, and horizontal article-supporting frames carried by the outer ends of the bracket arms, said frames being rotatably mounted to swing about a vertical axis, and dimensioned to swing into and out of the case through the 80 open front thereof.

In testimony whereof I affix my signature.

LESLIE JAMES.
